UNITED STATES PATENT OFFICE.

PETER SCHOFIELD, OF PHILADELPHIA, PENNSYLVANIA.

DEVICE FOR ATTACHING FAUCETS TO BARRELS.

SPECIFICATION forming part of Letters Patent No. 244,320, dated July 12, 1881.

Application filed March 12, 1881. (No model.)

To all whom it may concern:

Be it known that I, PETER SCHOFIELD, a citizen of the United States, residing in Philadelphia, Pennsylvania, have invented certain 5 Improvements in Devices for Attaching Faucets to Barrels, &c., of which the following is a specification.

The object of my invention is to so construct a device for attaching faucets to barrels, kegs, &c., that the application and removal of the faucet can be readily effected, leakage overcome, and the clogging of the outlet by the bung prevented. These objects I attain in the manner which I will now proceed to describe, 15 reference being had to the accompanying drawings, in which—

Figure 1 is a longitudinal sectional view of a faucet and my improved device for attaching the same to the barrel or other reservoir of liquid; Fig. 2, a longitudinal section of the device from which the faucet has been removed; Fig. 3, a transverse section on the line 1 2, Fig. 2; Fig. 4, a transverse section on the line 3 4, Fig. 1; and Fig. 5, a detached view, showing one of the minor features of the invention.

The faucet shown in the drawings is similar to that which forms the subject of my Letters Patent No. 163,263, dated May 11, 1875, A being the stem of the faucet, B the sliding tube 30 with discharge-nozzle and valve, and D the operating-nut, adapted to sections of screw-threads formed on the stem A and tube B.

A more detailed description of the faucet will be unnecessary, as the device forming the 35 subject of my present invention is adapted for use in connection with faucets of different characters.

F is a hollow tapering plug adapted to fit into the bung-hole of a barrel, keg, or other 40 reservoir containing liquid, the front end of the plug being made of sufficient strength to withstand the blows of the mallet used in driving the plug into its place. The plug F has a cylindrical bore, in which fits snugly, but so as 45 to slide freely, a tubular valve, G, having transverse openings *a a* and two annular packing-rings, *b d*, the ring *b* being in front of said openings *a* and the ring *d* in the rear of the same. The stem *e* of the valve G passes through 50 a bridge, *f*, in the hollow plug F, and between said bridge and a shoulder, *g*, on the valve-

stem intervenes a coiled spring, *h*, the tendency of which is to move the valve outward, an enlarged head, *m*, on the valve-stem serving, by contact with the bridge *f*, to limit said forward movement of the valve. (See Fig. 2.)

Before a faucet has been applied to the plug F the valve G occupies the position shown in said Fig. 2, being moved outward to its full extent by the spring *h*, so that the portion of 60 the valve having the transverse openings *a* formed therein occupies a position within the cylindrical bore of the plug, and the passage of the liquid to and through said openings *a* is prevented by the annular packing-ring *d*. 65 When the faucet is inserted into the plug, however, the inner end of the stem A presses upon the outer end of the tubular valve G and causes the latter to move inward, so that the 70 openings *a* are carried beyond the cylindrical bore of the plug, and the flow of liquid into and through the valve and through the faucet is thereby permitted. Leakage around the valve, when the latter is pushed inward, is prevented by the packing-ring *b* in advance of the 75 openings *a*, and leakage between the end of the valve and the stem of the faucet is prevented by the packing-ring *n*, carried by the annular shoulder, which presses upon said end of the 80 valve.

The inner end of the faucet-stem is preferably reduced in diameter, as shown, so as to fit into the central opening of the valve G; but this is not essential.

In order to permit the ready introduction 85 and withdrawal of the faucet without impairing the secure retention of the same when inserted, I form in the plug F transverse openings *s*, and in the faucet-stem A a transverse slot, *w*, the latter, when the faucet is inserted, 90 coinciding with the openings *s* and permitting the insertion of a transverse pin, *J*, whereby the faucet is firmly retained in the plug. By simply withdrawing the pin the faucet is free to be removed, the act of removal permitting 95 the closing of the valve G.

When the device is applied to ale-barrels I use, in place of the solid head *m* on the valve-stem, a perforated head, *m*, such as shown in Fig. 5, this head fitting snugly to the interior 100 of the tapering plug F, so that the liquid must pass through the perforations, the dregs or

lees being thereby prevented from passing to the faucet.

In the event of the failure of the plug F to drive the bung from the bung-hole when said plug is inserted therein, the head m of the valve-stem will effect the removal of the said bung when the valve is caused to move rearward by the insertion of the faucet into the plug.

10 I claim as my invention—

1. The combination of the plug F, having a cylindrical bore, the tubular valve G, having transverse openings a, and packing-rings b and d, arranged on opposite sides of said openings, as set forth.

2. The combination of the plug F, having transverse openings s, the sliding valve G, the tubular faucet A, having a transverse slot, w, in its periphery, and the transverse pin J, adapted to said slot and openings, as set forth. 20

In testimony whereof I have signed my name to this specification in the presence of two subscribing witnesses.

PETER SCHOFIELD.
